ARTIFICIAL FUR

Georges Romane, Saint-Mande, France

Application April 22, 1937, Serial No. 138,465
In France April 24, 1936

2 Claims. (Cl. 154—43)

The present invention relates to the manufacture of imitation astrachan fur. The fur according to the invention comprises essentially a suitable backing on which is applied by sticking or sewing or any other convenient means, gibbousé chenille, i. e., chenille the fibers of which have been laid circularly to form a roll or core, the said gibbousé chenille having been previously knotted more or less tightly at any points spaced 5 in such a manner that the volume of the chenille will vary and its surface will give irregular reflection of the light. The product obtained according to the present invention has an appearance closely resembling natural astrachan fur.

15 The invention is fully disclosed by the present specification with reference to the accompanying drawing, in which:

Figure 1 is a perspective view of a piece of knotted gibbousé chenille according to the invention.

20 Fig. 2 is a backing surface, partly covered with said knotted gibbousé chenille.

In practising my said invention, I first manufacture a gibbousé chenille, consisting of a roll or core made of textile material with crosswise-arranged fibers, laid circularly around the core. Said gibbousé chenille *a* is then knotted at convenient intervals, so as to present spaced knots *b*. The knotted gibbousé chenille thus obtained is

then stuck along a sinuous path on a convenient backing such as tissue, fabric or other skin-like suitable material.

The knots *b* which are thus irregularly distributed over the surface *c*, give the product the appearance of natural astrachan, by causing reflection of the light interrupted along the chenille, in such a manner that said chenille looks non-continuous, without it being necessary to cut said chenille in short pieces.

Moreover, each knot appears like a tuft, of a different volume than the unknotted portions of the chenille, so that the final product obtained looks like genuine fur.

Instead of giving to the knotted gibbousé chenille arrangement on the backing a design like astrachan, any other arrangement may be made in order to provide another fancy material.

I claim:

1. An artificial fur comprising a backing material having applied flatwise thereto gibbousé chenille knotted on itself with spaced knots.

2. An artificial fur comprising a backing material having applied flatwise thereto chenille gibbousé with spaced knots, said gibbousé chenille being fixed on said backing in a sinuous path.

GEORGES ROMANE.
